UNITED STATES PATENT OFFICE.

GRACE C. HARRIS, OF MONTEREY, CALIFORNIA.

CHILD-HOLDER ATTACHMENT FOR AUTOS.

1,366,798.

Specification of Letters Patent. Patented Jan. 25, 1921.

Application filed June 10, 1919. Serial No. 303,072.

To all whom it may concern:

Be it known that I, GRACE C. HARRIS, a citizen of the United States, residing at Monterey, in the county of Monterey and State 5 of California, have invented new and useful Improvements in Child-Holder Attachments for Autos, of which the following is a specification.

This invention has reference generally to 10 improvements in baby holders, and more particularly relates to a child holder for attachment to autos.

The invention has for its principal aim and object to provide a device of the above 15 mentioned character designed so as to accommodate one or more babies or children and in turn be connected within the rear part of the front seat of the motor vehicle so as to retain the children and avoid the ne- 20 cessity of bestowing continual attention on the children.

It is an equally important object of the present invention to provide a holder in the form of a bag or sack which is capable of 25 being adjusted horizontally and vertically to properly accommodate one or more children, while means are also employed for disposition about the children and engagement with the sack for maintaining the child or chil- 30 dren in a substantially upright form, even though they fall asleep.

As a more specific object the present invention contemplates the provision of im- 35 proved coöperative means on the sack or bag for removably and adjustably maintaining the sack in predetermined positions of ad- justment; and to improve the construction of the sack.

Among the other aims and objects of this 40 invention may be recited the provision of a device of the character described with a view to compactness, and in which the number of parts are few, the construction simple and the cost of production low and the efficiency 45 high.

Other improvements and novel details in the construction and arrangement of the various parts of the apparatus will be brought out more in detail in the description to follow, 50 and the accompanying drawings forming a part hereof, wherein is disclosed for the purpose of illustration a convenient and satisfactory embodiment of the invention. It is to be noted in this connection that minor 55 changes in the construction and arrangement of parts may be made without depart-

ing from the principle of operation of the various parts.

The invention is clearly illustrated in the accompanying drawings, in which:— 60

Figure 1 is a perspective view showing the device applied.

Fig. 2 is a perspective looking at the rear of Fig. 1.

Fig. 3 is a top plan view thereof. 65

Fig. 4 is a longitudinal sectional detail of the bag or sack.

Fig. 5 is a vertical sectional detail thereof.

Fig. 6 is an end elevation of the improved 70 baby holder.

Fig. 7 is a detail of the hanger strap.

Similar characters of reference are em- 75 ployed in all of the above described views, to indicate corresponding parts.

Referring now, more particularly, to the 80 accompanying drawings there is provided a sack or bag 1 which is formed from a single piece of suitable cloth which is folded upon itself and has its side edges secured together by stitches 2 in such a manner that the rear portion is longer than the front portion, 85 providing an extension 3. Another row of stitches 4 is provided in spaced relation to the stitches 2 so as to provide side casements 5 in which are disposed adjusting strips 6, 85 the lower ends of which are anchored as at 7 at the lower ends of the casing. These straps are provided with eyelets 8 and carry rings 9 at their outer ends, while engageable with the rings or any of the eyelets is a 90 snap hook 10 which is connected to another strap 11 in turn secured as at 12 to the opposite or rear portion of the body or bag. By the provision of these straps 6 and fasteners 9 it is apparent that the height of the 95 bag may be adjusted to accommodate various sized children.

In order to adjust the width of the bag to accommodate one or more children, as de- 100 sired, the upper edge of the front of the bag is folded inwardly and secured by stitches 13 to provide a casement 14, in which is mounted another strap 16, the intermediate portion of which is secured by a suitable fastener 17, while the respective end portions 105 carry eyelets 18, and rings 19 at the terminals thereof. Other straps 20 are connected rigidly as at 21 to the upper edges near the sides of the bag and these straps carry snap fasteners 22 designed to be engaged with 110 either the rings 19 or any of the eyelets 18.

In connecting the device in position, straps

23 and 24 and straps 25 and 26 are secured as at 27 to the upper edges of the extension 3, while the straps 23 and 25 carry buckles 28 for engagement respectively with the straps 24 and 26 subsequent to the passing of the straps about the handle bar 29 on the back of the front seat 30 of the motor vehicle 31, supporting the bag in the front of the front seat.

10 A pocket generally designated by the numeral 32 is secured to the front face of the extension 3 and accommodates a padding material or a pillow 33 which is removably maintained in position by means of a flap 34 15 detachably engageable, as at 35, with a pocket for covering the same.

In order that children may be held in a substantially upright position in the sack and even when they fall asleep, body engaging straps 36 are employed for disposition about the body of the child beneath the arms, one of the terminals of the strap carrying a buckle 37 for engagement with the opposite terminal. A tab 38 projects from the medial 25 portion of each strap 26 and carries an engaging loop 39 designed for engagement with any one of the buttons 40 carried by a flexible strap 41 and in turn secured to the upper edge of the extension on the front face 30 thereof, as indicated in the drawings. To afford the children amusement when in the bag, a pocket 40' is connected to the outer face of the front of the bag and is adapted to receive cakes, toys, et cetera, which are prevented from displacement by a flap 41'.

It is thought in view of the foregoing description that a further detailed description of the operation of the invention is entirely

unnecessary. Likewise it is believed that the advantages of the invention will be 40 readily apparent.

As many changes could be made in the above construction and many apparently widely different embodiments of this invention could be made without departing from 45 the scope thereof it is intended that all matter contained in the above description or shown in the accompanying drawings shall be interpreted as illustrative and not in a limited sense. It is also to be understood 50 that the language used in the following claim is intended to cover all the generic and specific features of the invention herein described and all statements of the scope of the invention which as a matter of language 55 might be said to fall therebetween.

What is claimed is:—

A device of the character described including a bag having casements formed at the sides thereof and a casement at the top 60 of the front, straps anchored at the bottom of the side casements and having eyelets in their outer portions, snap hooks flexibly connected to the top of the bag at the sides thereof and engageable with any of the eyelets 65 in the straps for varying the height of the bag, another strap disposed in the top casement and having eyelets in its projecting end portions, other snap hooks flexibly connected to the top of the bag and at the sides thereof 70 and engageable with any of the eyelets in the extending portions of the last mentioned strap for varying the width of the bag, and means for attaching the bag.

In testimony whereof I affix my signature. 75

MRS. GRACE C. HARRIS.
